C. A. ANDERSON

BOOMERANG THROWER

Filed July 3, 1922

Inventor:
C. A. Anderson
by night known only by may
Atty's.

UNITED STATES PATENT OFFICE.

CARL A. ANDERSON, OF BOSTON, MASSACHUSETTS.

BOOMERANG THROWER.

Application filed July 3, 1922. Serial No. 572,563.

To all whom it may concern:

Be it known that I, CARL A. ANDERSON, a subject of the King of Sweden, residing at Boston, in the county of Suffolk and State 5 of Massachusetts, have invented new and useful Improvements in Boomerang Throwers, of which the following is a specification.

This invention relates to a boomerang-throwing device including a flat-surfaced tablet adapted to support a boomerang in position to be thrown edgewise, a handle to be grasped by the operator, a spring adapted to be set for action by the operator, means actuated by the spring to impart a 10 forcible edgewise movement to a boomerang supported by the tablet, and a trigger adapted to releasably confine said spring-actuated means, and permit the same to act on the boomerang.

20 The invention is embodied in the improvements hereinafter described and claimed in a boomerang thrower characterized as above stated, the objects attained by said improvements being fully set forth hereinafter.

25 Of the accompanying drawings forming a part of this specification,—

Figure 1 is a side view of a boomerang thrower embodying the invention.

Figure 2 is a top plan view of the same.

30 Figure 3 is an enlarged fragmentary section on line 3—3 of Figure 2.

Figure 4 is a top plan view, the tablet being removed.

35 Figure 5 is a side view of a portion of the boomerang shown by dotted lines in Figures 1 and 2.

Figure 6 is a view similar to Figure 5, showing a modification.

40 The same reference characters indicate the same parts in all of the figures.

In the drawings, 12 represents a flat tablet, preferably of sheet metal, secured to a holder which includes a base portion on which the tablet is seated, bearings at one 45 end of the base portion, and a handle at the opposite end of said portion. The holder is preferably formed from an elongated metal strip, bent to form a looped central portion 13, constituting the handle, 50 parallel connected portions 14, riveted together at 15' (Figure 3) and constituting the base portion, and end portions 15 and 16, bent downward from the base-forming portions 14, and provided with ears 17 and 55 18, which are apertured at 19 to form the bearings which are spaced apart, as shown

by Figure 1. A rod 20 is journaled in said bearings, and is provided at its upper end with an angular arm 21, bent at 22, and provided at its outer end with an upstanding finger 23. 24 represents a helical spring, one end of which is engaged at 25 with the end portion 16, and the other end at 26, with the rod 20. A movement of the arm 21 to the full line starting position shown by Figures 1, 2, and 4, compresses the spring, so that the latter tends to force the arm to the dotted line stopping position shown by said figures. When the arm is in the starting position, the finger 23 projects across one end of the tablet 12, and when the arm is in the stopping position, the finger projects across the opposite end of the tablet. The arm is releasably confined in its starting position by the trigger herein-after described, and is arrested in its stopping position by the end portion 15 of the holder, as shown by Figure 4.

The trigger is composed of a resilient strip 28, attached at 29 to the handle portion 13, and a hooked terminal 30, attached to the free end of the strip and normally held by the latter against one side of the arm 21. The strip 28 extends beside the handle portion 13, and is arranged to form a finger rest on which a finger of the hand grasping the handle may be pressed to move the trigger in the direction of arrow α (Figure 1), and thereby release the arm.

The tablet is preferably secured detachably to the base portion of the holder, so that the tablet and holder may be separated and compactly stored. To this end I employ bolts 32, inserted in coinciding holes formed in the tablet and in the base portion 90 of the holder, said bolts having heads 33, bearing on the upper side of the tablet, and clamping wing nuts 34, engaging said bolts and bearing on the under side of the base portion of the holder.

To prevent obstruction of the upper surface of the tablet by the bolt heads, I provide the tablet with bosses 36, forming depressed portions on which the bolt heads are seated, said heads being flush with the upper surface of the tablet, as shown by Figure 3. The bosses 36 may be provided with slots 37 (Figure 2), arranged to receive the heads 33 (which are oblong), when the heads are turned from the position shown 105 by Figure 2, to coincide with the slots. The tablet may, therefore, be separated from the

holder without removing the bolts from the latter.

The rod 20 is loosely confined by the spring 24 in its bearings, so that it may be moved endwise when the tablet is detached. Provision is thus made for storing the arm 21 beside the holder in the right-hand dotted line position shown by Figure 4. To locate the arm in this position, the rod 20 is first moved upward in its bearings, until the arm is free to swing across the holder, then swung in the direction of arrow γ (Figure 4) across the holder, and then moved downward to cause the spring, now under relatively slight tension, to hold the arm against the holder.

40 represents a boomerang, which is a thin angular strip of any suitable material, such as hard rubber, vulcanized fiber, etc., adapted to lie flat on the upper surface of the tablet. In one end portion of the boomerang is an orifice 41, adapted to loosely receive the upstanding finger 23. When the arm 21 is confined in its starting position by the trigger, the boomerang is deposited on the tablet, its orifice 41 receiving the finger 23. When the trigger is manipulated to release the arm 21, the finger and the boomerang are swung around to the stopping position 30 of the finger. The tablet is provided with means for lifting the boomerang from the finger when the latter reaches or approaches its stopping position, said means being preferably an inclined strip 43, arranged to force 35 the boomerang upward until it leaves the finger. The boomerang is now forcibly projected from the tablet, and has an orbital movement, causing it to move first away from the throwing instrument, and then return to the neighborhood thereof.

I am not limited to the employment of means on the tablet for lifting the boomerang to disengage it from the finger 23. As shown by Figure 6, the boomerang may be 45 provided with an open slot 42, which receives the finger when the latter is in its starting position. When the finger is released by the trigger, it bears on the edge of the slot 42, and imparts a whirling edge-wise movement to the boomerang, until the arm approaches its stopping position, the slot then permitting the separation of the boomerang from the pin. It will be seen, therefore, that when the boomerang is provided with an opening, as the orifice 41, formed to surround the pin 23, lifting means, such as the incline 43, will be necessary, but when the opening is a slot 42, said lifting means will be omitted.

60 I claim:

1. A boomerang thrower comprising a tablet; a holder including a base portion attached to the tablet, bearings at one end of the base portion, and a handle at the opposite end of said portion; a rod journaled to

turn in said bearings and provided with an arm having an upstanding finger at its outer end; a spring engaged with said holder and rod, adapted to turn the latter in said bearings, a trigger carried by the holder and adapted to engage said arm and releasably confine the latter with its finger in a starting position at one end of the tablet, the finger being movable by the spring to a stopping position at the opposite end of the tablet, and adapted to enter an opening in a boomerang supported by the tablet, so that the finger, in moving from its starting to its stopping position, imparts a whirling edgewise movement to the boomerang, means being provided for permitting the projection of the boomerang from the thrower when the pin approaches its delivering position.

2. A boomerang thrower substantially as specified by claim 1, the said tablet being provided with depressed portions detachably secured to the base portion of the holder by bolts having heads which are flush with the upper surface of the tablet, and clamping nuts engaged with said bolts and bearing on the under side of the base portion.

3. A boomerang thrower substantially as specified by claim 1, the said tablet being provided with depressed portions detachably secured to the base portion of the holder by bolts having heads which are flush with the upper surface of the tablet, and clamping nuts engaged with said bolts and bearing on the under side of the base portion, said depressed portions being slotted to permit the release of the tablet from the holder by a partial rotation of the bolts.

4. A boomerang thrower substantially as specified by claim 1, said holder being composed of an elongated metal strip bent to form a looped central portion constituting the said handle, parallel connected portions constituting the said base, and end portions, bent downward from the base and provided with apertured ears forming said bearings.

5. A boomerang thrower substantially as specified by claim 1, the said trigger being composed of a resilient finger rest, attached to and extending beside the handle, and a hooked terminal on the free end of said rest, arranged to normally engage the said arm.

6. A boomerang thrower substantially as specified by claim 1, the tablet being detachably secured to the holder, and the rod being movable endwise in said bearings to permit the storing of the arm beside the base portion of the holder when the tablet is detached.

7. In combination, a boomerang having an opening in one end portion; and a thrower having a tablet adapted to support the boomerang, an oscillatory arm provided with a finger projecting above the tablet, means supporting said arm to permit oscillating movements thereof, a spring exerting

pressure on the arm in one direction, and a trigger adapted to releasably confine the arm in a predetermined position, the said boomerang opening being formed to loosely surround said finger, and the tablet being provided with means for lifting the boomerang from the finger.

8. In combination, a boomerang having an opening; and a thrower comprising a boomerang support, an oscillatory arm having a pin at its free end, adapted to enter said opening, means supporting said arm to permit oscillatory movements of the latter; a spring exerting pressure on the arm in one direction; and a trigger adapted to releasably confine the arm in a starting position from which the arm is movable in a curved path by the spring to a stopping position, so that the arm imparts a whirling edgewise movement to the boomerang in moving from one of said positions to the other, means being provided for permitting the projection of the boomerang from the thrower, when the pin approaches its stopping position.

In testimony whereof I have affixed my signature.

CARL A. ANDERSON.
